US00D759711S

(12) **United States Design Patent** (10) **Patent No.:** **US D759,711 S**
Seo et al. (45) **Date of Patent:** **** Jun. 21, 2016**

(54) **DISPLAY SCREEN OR PORTION THEREOF
WITH GRAPHICAL USER INTERFACE**

- (71) Applicant: **Samsung Electronics Co., Ltd.**, Suwon-si (KR)
- (72) Inventors: **Jang-Won Seo**, Seoul (KR); **Yong-Hwan Kwon**, Sungnam-Si (KR); **Ji-Eun Kim**, Suwon-Si (KR); **Ji-Hong Kim**, Seoul (KR); **Hyue-Ryung Kim**, Sungnam-Si (KR); **Se-Ran Jeon**, Seoul (KR); **Woo-Seok Hwang**, Seoul (KR)
- (73) Assignee: **Samsung Electronics Co., Ltd.**, Suwon-si (KR)

(**) Term: **15 Years**

(21) Appl. No.: **29/527,284**

(22) Filed: **May 18, 2015**

Related U.S. Application Data

- (62) Division of application No. 29/459,977, filed on Jul. 5, 2013, now Pat. No. Des. 740,313.

CLAIM

We claim the ornamental design for a display screen or portion thereof with graphical user interface, as shown and described.

DESCRIPTION

The FIGURE is a front view of the display screen or portion thereof with graphical user interface showing our new design. The outer broken line perimeter showing a display device is provided for the purpose of illustrating environmental structure and forms no part of the claimed design. The broken lines within the outer perimeter showing the display screen with graphical user interface is provided for the purpose of illustrating portions of the article that forms no part of the claimed design.
